UNITED STATES PATENT OFFICE.

JOHN T. WENYON, OF PHILADELPHIA, PENNSYLVANIA, ASSIGNOR OF ONE-HALF TO
DANIEL J. GORMAN, OF PHILADELPHIA, PENNSYLVANIA.

GAME.

1,216,382.

Specification of Letters Patent. Patented Feb. 20, 1917.

Application filed May 12, 1916. Serial No. 97,052.

To all whom it may concern:

Be it known that I, JOHN T. WENYON, a subject of the King of Great Britain, and a resident of the city of Philadelphia, county of Philadelphia, and State of Pennsylvania, have invented certain new and useful Improvements in Games, of which the following is a full, clear, and exact disclosure.

The object of the invention is to provide an improved device for the projection of rings, or the like, from a given position upon a relatively flat surface, upwardly into the air, whence it is designed to drop upon any one of a set of pins, or to one side of the latter.

Another object of the invention is to provide a ring for use with a game of this character, which has a weight secured to one portion thereof, the said weight having the effect of deflecting the course of the said ring to one side or the other, after it has left the direct influence of the mechanism, which gives to it its initial impulse.

And still another object is to provide a device of this character, with suitable and efficient means whereby the rings may be returned to the operator, or adjacent to the starting point, to then be made again available by releasing a trap or door by suitable coin-operated mechanism.

Further objects and details of the construction of the preferred embodiment of the invention are fully brought out in the following description, when read in conjunction with the accompanying drawings, in which Figure 1 is a perspective view of the improved game, and Fig. 2 is a vertical, longitudinal section of the same.

Referring to the drawings, the device comprises a platform 1, raised upon a suitable support 2, and inclosed at its sides and rear by an upright screen 3, while from the forward edge of said platform slopes an inclined surface 4, adjacent to the forward portion of which is pivotally mounted a trap, or door 5, opened by pressure of the foot upon a tread 6, upon releasing the said door by a suitable coin-operated mechanism 7, to which leads a slot or track 8, into the uppermost end of which a coin may be inserted.

The sides of the device, as well as the space above and below the slanting surface 4, are inclosed by walls 9, and between the latter and at the forward portions thereof ex-

tends a transversely positioned platform 12, curving gradually upwardly at its rearward portion for a purpose hereinafter described. Resting slidably upon said platform 12 is a projecting member comprising a metallic plate 13, adapted to support a ring 14 having secured thereto any suitable weight 15, the plate 13 being provided with a raised portion 16 having a semicircular recess against the walls of which said ring bears.

Projecting downwardly from said plate 13 and passing through a slot 18 in the platform 12 is a pin 19, carrying a plunger 20, which in turn is pulled forwardly by the handle 21, against the pressure of the expansion spring 22. Secured upon the upper surface of the platform 12 are also diverging raised members 23, between which the ring 14 is projected toward the rear of the device, after pulling the handle 21 and plate 13, operated thereby outwardly, and releasing the same, which latter operation permits the spring to force said plate suddenly rearwardly until brought suddenly to a stop by the spring or cushion 19'. The whole of the projecting mechanism is covered by a plate 25, which keeps the former free from dust and dirt, as well as preventing interference therewith.

The object of the device as before stated is to shoot the ring from the platform 12, up into the air and thence to permit the said ring to fall in such manner upon the platform 1 as to encircle one of the upright spikes 26, or the like, while in any event the said ring upon falling rests upon a screen or net 27, instead of directly upon the said latter platform. When all of a given number of the said rings have been used, and it is desired to regain possession of them, a coin is inserted in the slot 8 and the door 5 opened by pressure of the foot upon the pedal 6. As the door swings outwardly, it pulls a string 28, which passes to the rear, around a pulley 29, and by means of any suitable lever 30, co-operating with the screen 27, it raises the latter, tilting the same upwardly, thereby freeing the rings from the spikes or pins 26 and permitting the former to slide on to the surface 4 to where they can be reached by the operator. The door is then closed, thus returning the screen 27 to its normal slightly inclined position, and the apparatus is in position to operate as before.

It will be noted that, if the weight carried by the ring lies to the rear and center, said ring with the proper force applied thereto by the spring 22 will have a tendency to fall in a substantially horizontal position upon the platform, or rather the screen 27, but if the said weight lies to either side of the point mentioned it will have a tendency to depress that side of the 10 ring and practically, if not entirely, prevent the latter from falling in such manner as to encircle one of the pins as before described.

While one form of the invention has been described, and the details characteristic 15 thereto, the principle in its broadest form it is desired to protect, with any changes or alterations in the shape or detailed construction of the elementary parts of the device, wherefore the present form of the invention and the claims hereto appended should not be restricted to the exact form 20 shown.

Having thus described my invention, what I claim and desire to protect by Letters Patent of the United States is:—

1. A device, comprising a ring projecting mechanism, a screen, and a coin-released mechanism adapted to permit the manual elevation of said screen to return by gravity 30 a ring projected thereupon by said mechanism.

2. A device, comprising a manually-released spring-operated ring projecting mechanism, a series of upright pins, a pivoted screen surrounding said pins, and a manually operated coin-released mechanism adapted to permit the elevation of said screen to release a ring projected by said first mechanism upon said pins and to permit said ring to move therefrom by gravity. 40

3. A device, comprising a platform, a series of pins or spikes, a screen surrounding said pins and pivotally mounted to tilt upwardly to release a ring from said pins and permit said ring to move therefrom by 45 gravity, and manually operated means to tilt said screen.

4. A device, comprising a receptacle for a ring, resilient means to actuate the same, means to manually set the former into operation, the whole comprising a projecting device adapted to shoot a ring, an upwardly curved platform to alter the course of said ring, a pivotally mounted screen, through which normally project pins, and adapted 55 to be tilted to free a ring from said pins, and coin-released manually-operated means to tilt said screen to return said ring to an operator.

In witness whereof, I have hereto set my 60 hand this 11th day of May, A. D. 1916.

JOHN T. WENYON.
